CLAIM

The ornamental design for a massaging nursing bracelet, as shown and described.

DESCRIPTION

FIG. 1 is a perspective view of a massaging nursing bracelet showing my new design;

FIG. 2 is a top view thereof;

FIG. 3 is a front view thereof;

FIG. 4 is a back view thereof;

FIG. 5 is a side view thereof; and,

FIG. 6 is a side view thereof.

The broken line showing of the numbers is included for the purpose of illustrating use and environment and forms no part of the claimed design.
